(57) **CLAIM**

We claim the ornamental design for a caulk tool, as shown and described.

DESCRIPTION

FIG. 1 is a top, front, right perspective view of a caulk tool showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a bottom, front, left perspective view; and,

FIG. 9 is a perspective view of the caulk tool in folded position.

The broken lines in the drawings illustrate portions of the caulk tool which form no part of the claimed design.
